TUBE

Raymond E. T. Haff, White Plains, N. Y., assignor
to Du Pont Cellophane Company, Inc., New
York, N. Y., a corporation of Delaware

Application January 22, 1932. Serial No. 588,094

9 Claims. (Cl. 250—27.5)

This invention relates to tubes, such as radio tubes and the like, and particularly to tubes provided with temporary coverings designed and constructed to permit the tubes to be electrically tested and not to permit actual use of the tubes without rupturing or mutilating said coverings.

In the sale of radio tubes and the like, it is the customary practice to test the tube in the presence of the purchaser in order to assure him that he is securing a perfect tube. Many used tubes when tested give a positive result with the consequence that they are sold as new. When a used tube is sold it becomes exhausted during a period of time considerably less than its guaranteed life. As a consequence, the user complains to the manufacturer and demands replacement. Again, many dealers quite frequently return to the manufacturer used or burned out tubes as defective ones. It is apparent that these practices not only are expensive to the manufacturer but also tend to destroy the good will built up by him.

I have found that I can overcome the above difficulties by providing a protective covering adjacent the contact members of a tube with conducting means to permit electrical contact to be made with the contact members for testing purposes, but not to permit actual use of the tubes without rupturing or mutilating the protective covering.

It is, therefore, an object of this invention to provide a tube having contact members in the base thereof whereby the tube may be disposed in an electrical circuit and the filament and appurtenant elements in the tube energized with a temporary protective covering adjacent the ends of the contact members of the tube having conducting means adapted to permit testing, but not to permit use of the tubes without disrupting or mutilating the protective covering.

Other objects of this invention will appear from the following description, appended claims and accompanying drawing forming a part of this specification and in which:

Figure 1 is a side elevation partly in section of a radio tube with one form of protecting covering and contact elements cooperating with the contact members or prongs.

Figure 2 is a partial view similar to Figure 1 of a modified form of protective covering.

Figure 3 is a view similar to Figure 2 illustrating another modified form of protecting covering with modified contact elements.

Referring to the embodiments of the invention illustrated in the drawing, and particularly

to Figure 1 thereof, the numeral 1 designates the bulb of a radio tube carried on a base 2 supporting the filaments 3 and their appurtenant parts which are also on the base 2. The exposed end of the base 2 is provided with a plurality of contact members or prongs 4 by means of which, when positioned in the sockets, the tube is placed in the electrical circuit. Disposed in cooperative relation with the ends of the prongs 4 is a non-conducting disc 5 which may be of cardboard, paper, regenerated cellulose, or other suitable material. The disc 5 is provided with conducting means, such as metal contacts 6. These metal contacts may be secured in apertures in the disc 5 in any suitable manner, such as by riveting or otherwise. One of the metal contacts 6 is adjacent or in contact with the end of each prong 4. The disc 5 is supported on an annular ring 7 of cardboard or other suitable material which engages with the bottom 8 of the base 2 and extends for a distance approximately equal to the exposed length of the prongs 4. To securely attach the parts together, a band 9 is used. For reasons which will become apparent, the band 9 is preferably formed of material which possesses the property of shrinking to a considerable degree upon conversion from a wet to a dry state. As a few illustrative examples of materials which possess this property may be mentioned regenerated cellulose, cellulose acetate and gelatin.

The parts may be assembled in various ways. For example, the band is made oversize and maintained in the wet state until used. After being slipped into position, the band greatly contracts as it dries, causing an annular flange portion 10 to form at the upper end thereof to secure the disc 5 and ring 7 to the tube base 2, and forms an annular contracted flange 11 at the other end smaller than the adjacent part of the base 2, thereby preventing the band 9 from being slipped off of the base.

In the form of the invention illustrated in Figure 2, the metal contacts 6 are carried in a disc portion 12 similar to the manner described concerning Figure 1. The disc portion 12 forms the top of an inverted cup-shaped cap 13 of paper, cardboard, or other suitable material. The cylindrical portion 14 of the cup may be formed in any desired way as by drawing the edges of a flat sheet of paper or light cardboard down over the base of the tube, thus forming a pleated skirt all around. The cap 13, after being slipped into position with the metal contacts 6 engaging the ends of the prongs 4, may be secured in position by shrinking in place a band 15 of suitable

material, such as described in connection with Figure 1. If desired, the lower edge 16 of the tubular portion of the cap may extend below the edge of the base 2 so as to be pressed inwardly by the band 15 to securely anchor the cap 13 to the base of the radio tube.

In the form of the invention illustrated in Figure 3, the disc 5 is provided with metal contacts in the form of metal eyelets 17 which permit easy alignment with the prongs of the tube. The eyelets may be riveted in apertures formed in the disc 5. Each eyelet 17 is arranged with its aperture 18 over the end of one prong 4. The apertures 18 are preferably of smaller diameter than the diameter of the prongs 4.

When a purchaser desires to buy a tube, it is usual for the dealer to remove it from the box in which it is packed, for the purpose of testing the tube. The purchaser, of course, can observe the protecting covering and determine if the tube is factory new. By means of a suitable testing socket having prongs adapted to press against the metal contacts, it can be readily determined whether or not the tube is in perfect operating condition by virtue of the current from the testing socket passing through the metal contacts and the contact prongs 4 of the tube.

To insert the tube in a circuit in use, the protective covering illustrated in the various figures of the drawing is removed in any suitable way as by an implement, such as an ordinary pocket knife, or by tearing the covering off of the base of the tube.

Though the invention has been described with specific reference to tubes having contact prongs, it is apparent that the principles thereof are equally applicable to other types of tubes. For example, the invention may be used in combination with incandescent lamps. In such a case, a protective covering of paper, cardboard or other suitable material is disposed on the base of a lamp with a metal contact member in alignment with the center contact of the lamp, the covering being secured in position by means of a band of regenerated cellulose or other suitable material shrunk into position to engage a portion only of the threaded periphery of the base. By means of the metal contact member and the exposed portion of the threaded base, the lamp may be tested prior to use. Due to the fact that the band is disposed about part of the threads of the base, it will be necessary to remove the band and protecting covering before the lamp can be actually used. It will be obvious that the invention may also be used in combination with incandescent lamps of the type which have end contacts without any threaded peripheral contacts on the base.

The invention may be embodied in other specific forms without departing from the spirit or essential characteristics of the invention, and the present embodiment of the invention is, therefore, to be considered in all respects as illustrative and not restrictive, the scope of the invention being indicated by the appended claims rather than by the foregoing description and all changes which come within the range of equivalents of the claims are therefore intended to be embraced therein.

I claim:

1. In combination with a tube having contact prongs extending from the base thereof whereby the tube may be inserted in an electrical circuit and the filament and appurtenant elements of the tube may be energized, supporting means extending from the base to approximately the

plane of the prong ends, and a temporary protecting element supported on the supporting means and having a non-conducting covering provided with contact elements, each of which contact elements is adjacent and adapted to engage a prong. 80

2. In combination with a tube having contact prongs extending from the base thereof whereby the tube may be inserted in an electrical circuit and the filament and appurtenant elements of the tube may be energized, supporting means extending from the base to approximately the plane of the prong ends, a temporary protecting element supported on the supporting means and having a non-conducting covering provided with contact elements, each of which contact elements is adjacent and adapted to engage a prong, and means to seal the supporting means and protecting elements to the base. 85

3. In combination with a tube having contact prongs extending from the base thereof whereby the tube may be inserted in an electrical circuit and the filament and appurtenant elements of the tube may be energized, supporting means extending from the base to approximately the plane of the prong ends, a temporary protecting element supported on the supporting means and having a non-conducting covering provided with contact elements, each of which contact elements is adjacent and adapted to engage a prong, and means to seal the supporting means and protecting elements to the base. 90

4. In combination with a tube having contact prongs extending from the base thereof whereby the tube may be inserted in an electrical circuit and the filament and appurtenant elements of the tube may be energized, a supporting ring extending from the base to approximately the plane of the prong ends, and a temporary protecting element supported on the supporting means and having a non-conducting covering provided with contact elements, each of which contact elements is adjacent and adapted to engage a prong. 95

5. In combination with a tube having contact prongs extending from the base thereof whereby the tube may be inserted in an electrical circuit and the filament and appurtenant elements of the tube may be energized, a supporting ring extending from the base to approximately the plane of the prong ends, a temporary protecting element supported on the supporting ring and having a non-conducting covering provided with contact elements, each of which contact elements is adjacent and adapted to engage a prong, and a band shrunk into position to seal the supporting means and protecting element to the base. 100

6. In combination with a tube having contact prongs extending from the base thereof whereby the tube may be inserted in an electric circuit and the filament and appurtenant elements of the tube may be energized, a temporary protecting element comprising an inverted cup-shaped cap, the skirt thereof cooperating with the base of said tube and the top thereof being provided with contact elements, each of which is adjacent and adapted to engage a prong of said tube. 110

7. In combination with a tube having contact prongs extending from the base thereof whereby the tube may be inserted in an electric circuit and the filament and appurtenant elements of the tube may be energized, a temporary protecting element comprising an inverted cup-shaped 115

cap, the skirt thereof cooperating with the base of said tube and the top thereof being provided with contact elements, each of which is adjacent and adapted to engage a prong of said tube, and 5 means to seal said cap in position.

8. In combination with a tube having contact prongs extending from the base thereof whereby the tube may be inserted in an electric circuit and the filament and appurtenant elements 10 of the tube may be energized, a temporary protecting element comprising an inverted cup-shaped cap, the skirt thereof cooperating with the base of said tube and the top thereof being provided with contact elements, each of which 15 is adjacent and adapted to engage a prong of said tube, and a band cooperating with said

skirt and tube base to seal said cap in position.

9. In combination with a tube having contact prongs extending from the base thereof whereby the tube may be inserted in an electric circuit and the filament and appurtenant elements 80 of the tube may be energized, a temporary protecting element comprising an inverted cup-shaped cap, the skirt thereof cooperating with the base of said tube and the top thereof being provided with contact elements, each of which is adjacent and adapted to engage a prong of 85 said tube, and a band shrunk in position, said band cooperating with said skirt and tube base to seal said cap in position.
